Application July 12, 1946, Serial No. 682,986
In the Netherlands February 22, 1943

Section 1, Public Law 690, August 8, 1946
Patent expires February 22, 1963

5 Claims. (Cl. 315—5)

1

This invention relates to a device for ultra-high frequencies comprising at least one discharge tube, whose wall consists of insulating material and which has at least one anode and one cathode, at least the anode circuit including a resonator which is tuned to the operating frequency and consists of two coaxial conductors and is at least substantially closed on all sides.

In the construction of such a device one is confronted with various problems. To obtain a satisfactory efficiency it is necessary, for instance, that the connecting leads between the resonator and the electrodes of the discharge tube(s) should be very short, since these leads cause considerable radiation and conduction losses which are proportional to the length of the connecting leads.

A second problem one is faced with is related with the heating of the seals of the said connecting leads i. e. those points of the wall of the tube, which may consist of glass, where the conductors conveying the high-frequency current are passed through this wall. This heating is due to the losses in the leads and may render the tube defective.

The present invention envisages a construction of the device referred to in the preamble, by which the aforesaid problems are solved satisfactorily. According to the invention this is achieved by means of a construction in which the inner conductor of the resonator is tubular, and one end of the inner conductor, which is not connected to the outer conductor, surrounds the discharge tube coaxially over a large part of the length of the anode in such a manner that the anode is capacitatively coupled to the inner conductor.

When making use of the construction according to the invention the connecting lead between anode and resonator, which lead causes the larger part of the losses because the voltages are a maximum at the anode, may be entirely dispensed with. Furthermore, since the tube is lodged at least for the greater part within the closed resonator, the radiation losses due to electromagnetic radiation from the electrode themselves are only small and the remaining connecting leads conveying high-frequency current can also be kept short; in a suitable form of construction set out hereinafter the part of the grid lead outside the tube may even be dispensed with completely.

In the construction according to the invention the seals are not heated or only to a slight degree, since in this case the connecting leads for the

2

electrodes, at least for the anode, passing through the insulating wall of the tube only serve for the supply of the feed voltages required for the electrodes, so that practically no losses occur in these leads.

In order that the invention may be clearly understood and readily carried into effect, it will now be described more fully with reference to the accompanying drawing which represents a preferred embodiment of a device according thereto in axial section.

The form of construction of a device according to the invention represented in the single figure of the drawing serves for the production of oscillations having the natural frequency of a resonator 1 which consists of a tubular inner conductor 3 and an outer conductor 5 surrounding the latter coaxially. The inner conductor 3 is connected at one end to the corresponding end 15 of the outer conductor 5, through the intermediary of a conductive disc 7. The other end of the outer conductor is terminated by a conductive disc 9 so that the resonator is closed practically on all sides. The resonator 1 is included in the anode circuit of a discharge tube 11 having an envelope 12 of insulating material. According to the invention the tube 11 is lodged within the tubular inner conductor 3 and this tube is coaxially surrounded by the end of the inner conductor 3, which is not connected to the outer conductor, over a great part of the length of the anode 13 in such a manner that the anode 13 is capacitatively connected to the inner conductor 3.

At the end of the inner conductor connected 35 to the disc 7 a potential node occurs, whereas a potential loop appears at the end to which the anode is coupled.

For supplying the required feed voltage to the anode conveying a high-frequency voltage use 40 is made of coaxial auxiliary conductor 15 having the same shape and substantially the same section as the inner conductor 3 and being incorporated in the tubular inner conductor 3 in such a manner as to be insulated therefrom. One end 45 of this auxiliary conductor is connected through a short connecting lead to the anode 13, whereas the other end, which preferably slightly projects from the resonator 1, is connected, through a connecting lead 17 outside resonator, to a source of anode voltage 19. As a result of the short distance in this construction between the cylindrical surface of the auxiliary conductor 15 and the inner surface of the inner conductor 3 these conductors are tightly coupled capacitatively and

constitute an assembly in electrical respect in regard to the operating frequency, so that the end of the conductor 15 projecting from the resonator and the lead 17 connected to this end does not have a high-frequency voltage relatively to earth.

The grid 21 of tube 11 is connected to the centre of the disc 9 through the intermediary of one or more connecting leads which are connected in parallel and are as short as possible. This centre and the end of the inner conductor 3 surrounding the anode constitute the electric terminals of the resonator. Consequently, the grid and the anode of the tube 11 are connected respectively to the electric terminals of the resonator.

The device represented in the drawing is of a type known per se, in which the resonant circuit is interposed between grid and anode and the cathode is connected to a point of a capacitative potentiometer connected in parallel with the resonant circuit and consisting of the cathode-anode capacity and the cathode-grid capacity. Between the cathode and the earthed outer wall of the resonator is included a circuit that is substantially tuned to the frequency of the oscillations to be generated and in the device shown in the drawing is constituted by a coaxial transmission line consisting of the conductors 23 and 25. The outer conductor 23 is connected to the earthed wall 9 of the resonator 1 in the proximity of the end facing the cathode, whereas the inner conductor 25 is earthed at the end of the resistance 31 remote from the cathode, which resistance serves for the obtainment of the required grid bias. The inner conductor 25, which serves at the same time for the supply of the required heating current, is tubular and contains the other heating lead which is insulated therefrom. The disc 9 is provided with a central aperture through which the two heating leads are connected to the cathode 27. The feed voltage for the cathode is supplied by a supply 29 one of whose terminals is earthed across the cathode resistance 31. The resistance 31 is preferably not bridged by a short-circuit condenser so that a negative back-coupling is present for the low frequencies thus preventing the tube 11 from oscillating at the desired frequency and at the same time at a low frequency.

The transmission line 23, 25 is tunable by means of a short-circuit bridge 33 which is movable in an axial direction. In view of the fact that the outer conductor 23 is earthed in regard to direct current, whereas the inner conductor 25 has a positive direct voltage with respect to earth, the bridge 33 is realised in such a manner that there is no electrical connection in regard to direct current between the conductors 23 and 25.

The device set out above generates oscillations whose frequency is determined by the natural frequency of the resonator 1. The frequency of the generated oscillations is variable by means of a conductive piston 41 which is movable in an axial direction with the aid of a clasp 43 projecting from the resonator.

The generated oscillations may be taken from the resonator by means of a loop 45 coupled to the magnetic field within the resonator.

In order that the coupling between the inner conductor 3 and the anode 13 may be controlled the inner conductor 3 is so realised as to be movable in an axial direction relatively to the tube 11 secured to the disc 9. With the aid of

a screw 47 the inner conductor 3 can be fixed in the desired position.

The envelope 12 of tube 11 extending for the greater part of the high-frequency electric field between the anode 13 and the end of the inner conductor 3, use is preferably made of a tube 11 with an envelope of a material having low dielectric losses such as quartz.

For carrying off the heat dissipated by the anode 13 use is made of liquid cooling in the device shown in the drawing. To this end the inner conductor 3 has a double wall and is equipped with two partitions extending in a plane through the axis of the inner conductor and dividing the space between the two walls of the inner conductor 3 into two compartments which communicate with each other at the end of the inner conductor surrounding the anode. These partitions are normal to the plane of the drawing; for clarity, however, they have not been represented. The cooling liquid can be supplied through an inlet opening 49 at the end of the inner conductor remote from the anode 13 to one of the two compartments, and upon traversing the other compartment of the inner conductor it is carried off through an outlet opening 51. To promote as much as possible the transfer of heat between the anode 13 and the inner conductor 3 preferably the inner side of the inner conductor 3 is coated with a black layer at the anode 13. When the tube 11 is of the usual type, where the anode consists of carbon, an effective transfer of the heat to be dissipated is obtained in this manner by radiation.

In the device according to the invention cooling by air instead of liquid cooling may be used, if desired; in this case the cooling air may be blown through an aperture, for instance through the aperture through which pass the heating current conductors the air then passing between the wall of the tube 11 and the inner wall of the inner conductor 3 and escaping to the outside through the inner conductor.

What I claim is:

1. An ultra high frequency electronic device comprising an electron discharge tube having an insulating envelope with a cathode, a grid and an elongated tubular anode enclosed therein, said grid and said cathode being coaxially positioned within said anode, and a reentrant cavity resonator having a tubular outer conductor surrounding said tube and a tubular inner conductor coaxial with said outer conductor and connected to one end thereof, the other end of said outer conductor being closed, said tube being received within said inner conductor to an extent at which a portion of said anode is surrounded by said inner conductor to effect capacitive coupling for high frequencies therebetween, said envelope acting as a dielectric between said anode and said inner conductor, said grid being connected to said closed end of said outer conductor.

2. An ultra high frequency electronic device comprising an electron discharge tube having an insulating envelope with a cathode, a grid and an elongated tubular anode enclosed therein, said grid and said cathode being concentrically arranged within said anode, a reentrant cavity resonator having a tubular outer conductor surrounding said tube and a tubular inner conductor coaxial with said outer conductor and connected to one end thereof, the other end of said outer conductor being closed, said tube being received within said inner conductor to an extent at which a portion of said anode is surrounded by said

inner conductor to effect capacitive coupling for high frequencies therebetween, said envelope acting as a dielectric between said anode and said inner conductor, said grid being connected to said closed end of said outer conductor, a cylindrical conductor coaxially disposed within said inner conductor, and means to apply an energizing potential through said cylindrical conductor to the anode of said tube.

3. An ultra high frequency electronic device comprising an electron discharge tube having an insulating envelope with a cathode, a grid and an elongated tubular anode enclosed therein, said grid and said cathode being coaxially positioned within said anode, a reentrant cavity resonator having a tubular outer conductor surrounding said tube and a tubular inner conductor coaxial with said outer conductor and connected to one end thereof, the other end of said outer conductor being closed, said tube being received within said inner conductor to an extent at which a portion of said anode is surrounded by said inner conductor to effect capacitive coupling for high frequencies therebetween, said envelope acting as a dielectric between said anode and said inner conductor, said grid being connected to said closed end of said outer conductor, a cylindrical conductor coaxially disposed within said inner conductor, means to apply an energizing potential through said cylindrical conductor to the anode of said tube, and an annular shorting bridge slidably arranged between said inner and outer conductors.

4. An ultra high frequency electronic device comprising an electron discharge tube having an insulating envelope with a cathode, a grid and an elongated tubular anode enclosed therein, said grid and said cathode being coaxially positioned within said anode, a reentrant cavity resonator having a tubular outer conductor surrounding said tube and a tubular inner conductor coaxial with said outer conductor and connected to one end thereof, the other end of said outer conductor being closed, said tube being received within said inner conductor to an extent at which a portion of said anode is surrounded by said inner conductor to effect capacitive coupling for high frequencies therebetween, said envelope acting as a dielectric between said anode and said inner conductor, said grid being connected to said closed

50

end of said outer conductor, a cylindrical conductor coaxially disposed within said inner conductor, means to apply an energizing potential through said cylindrical conductor to the anode of said tube, an annular shorting bridge slidably arranged between said inner and outer conductors, a coaxial transmission line having one end of its outer lead secured to said closed end of said outer conductor and having the corresponding end of its inner lead connected to the cathode of said tube, a capacitive bridge interposed between said inner and outer leads for tuning said line, and a cathode resistor connected between the other end of said inner lead and the outer surface of said outer conductor.

5. An ultra high frequency electronic device comprising an electron discharge tube having a tubular insulating envelope with a cathode, a grid and an elongated tubular anode enclosed therein, said grid and said cathode being coaxially disposed within said anode, and a reentrant cavity resonator having a tubular outer conductor surrounding said tube and a tubular inner conductor coaxial with said outer conductor and connected to one end thereof, the other end of said outer conductor being closed, said tube being received coaxially within said inner conductor to an extent at which a portion of said anode is surrounded by said inner conductor to effect capacitive coupling therebetween, said envelope acting as dielectric between said anode and said inner conductor, said grid being connected to said closed end of said outer conductor.
